[57] CLAIM

The ornamental design for a luminaire or similar article,
substantially as shown and described.

DESCRIPTION

FIG. 1 is a perspective view of a luminaire or the like
showing my new design;

FIG. 2 is an elevational view of the end opposite that
shown in FIG. 1 on an enlarged scale;

FIG. 3 is a rear elevational view thereof on an enlarged
scale;

FIG. 4 is a top plan thereof on an enlarged scale;

FIG. 5 is a bottom plan view thereof on an enlarged
scale.
